United States Patent Office.

GEORGE WILKINSON, OF PROVIDENCE, RHODE ISLAND, ASSIGNOR TO
GORHAM MANUFACTURING COMPANY, OF SAME PLACE.

Design No. 3,778, dated November 30, 1869.

DESIGN FOR A CASTER.

The Schedule referred to in these Letters Patent and making part of the same.

To all whom it may concern:

Be it known that I, GEORGE WILKINSON, of the city and county of Providence, and State of Rhode Island, have originated a new Design in Articles of Silver and Plated Ware, for a Caster, numbered 0,350, of which the accompanying photograph, with this specification, is a full and complete description; that is to say, the article of a caster, substantially as shown in the said photograph.

Claim.

The design for a caster, No. 0,350, substantially as herein set forth.

GEO. WILKINSON.

Witnesses:

HENRY E. LATHROP,
JOHN F. P. LAWTON.
